United States Patent Office.

SAMUEL E. CONDON, OF WILLIAMSBURG, NEW YORK.

Letters Patent No. 74,800, dated February 25, 1868.

IMPROVEMENT IN CURLING-IRONS.

The Schedule referred to in these Letters Patent and making part of the same.

TO ALL WHOM IT MAY CONCERN:

Be it known that I, SAMUEL E. CONDON, of Brooklyn, in the county of Kings, and State of New York, have invented a new and useful Improvement in Curling-Irons; and I do hereby declare that the following is a full, clear, and exact description thereof, which will enable others skilled in the art to make and use the same, reference being had to the accompanying drawings, forming part of this specification.

The present invention relates to irons used for curling in the dressing of a person's hair, and consists in providing the case with a spring-catch, fitting over a flange upon the handle of the iron, for securing it within the case, as will be hereinafter more particularly described.

In curling-irons as heretofore constructed, the case was not secured to the iron, and was, therefore, constantly dropping off when in use, subjecting the operator to the danger of being burned. In the accompanying plate of drawings, my improvement in curling-irons is illustrated—

Figure 1 being a side view to the case, broken out to show the iron, and

Figure 2 a transverse section, taken in the plane of the line x x , fig. 1.

Similar letters of reference indicate corresponding parts.

A, in the drawings, represents the curling-iron, provided at one end with a suitable handle, B, for convenience in using it. C, a casing to iron A, made of a suitable size and shape therefor, with one end, D, closed, and the other, E, open, and there provided with a spring-catch, F, of suitable form to set over and engage with the flange, G, to the iron at its handle-end, and thus secure and hold the case upon the iron, A.

In the use of the iron, provided with a case, as above described, the iron itself is first heated, as with ordinary curling-irons, and then inserted in the case C, to which imparting its heat it is used for the curling of the hair.

By means of the case, a smooth and even surface is always secured for the hair, as it is not the surface of the iron itself that is used, but that of the case thereto; and, as the iron only is inserted in the fire, or subjected to the other heated medium used, no "scalding" to the case can possibly occur.

Although, in the present description, only one form of curling-iron is shown, I desire it to be distinctly understood that I do not intend to limit myself to any one particular shape thereof, as my invention may be applied to all forms of such irons.

I claim as new, and desire to secure by Letters Patent—

The curling-iron A, when secured in the metal case C by means of the catch F upon the case, fitting over the flange G upon the handle B, as herein shown and described.

The above specification of my invention signed by me, this thirteenth day of August, 1867.

SAMUEL E. CONDON.
